UNITED STATES PATENT OFFICE.

THOMAS HENRY KANE, OF YOUNGSTOWN, OHIO, ASSIGNOR TO TRUSSSED CONCRETE
STEEL COMPANY, OF DETROIT, MICHIGAN, A CORPORATION OF MICHIGAN.

BENDING-MACHINE.

957,609.

Specification of Letters Patent. Patented May 19, 1910.

Application filed August 16, 1909. Serial No. 942,959.

To all whom it may concern:

Be it known that I, THOMAS H. KANE, a citizen of the United States, and a resident of Youngstown, in the county of Mahoning and State of Ohio, have invented a new and Improved Bending-Machine, of which the following is a specification.

This invention relates to machines for bending metal sheets into arcs of circles, and the object of this present construction is to provide a bending-machine which can be easily adjusted to bend ribbed or corrugated sheet-metal to arcs of any desired radius, by rolling.

This invention consists in combination with a pair of rolls, of an adjustable apron to control the curvature of the metal sheets.

It further consists of a novel reversing device for the rolls.

In the drawings Figure 1 is a rear elevation of the bending machine, a portion of the frame being broken away on the line 1-1 of Fig. 2. Fig. 2 is a vertical cross section on the line 2-2 of Fig. 1. Fig. 3 is a plan of the rear portion of the table. Fig. 4 is a plan of the reversing device. Fig. 5 is a detail of the reversing device. Fig. 6 is a view on a larger scale showing ribs and grooves of the rolls.

Similar reference characters refer to like parts throughout the several views.

This machine is principally designed for bending corrugated or ribbed sheet metal, but especially the ribbed expanded-metal shown in the Kane patent of May 4th 1909, No. 920,152. The legs 1 support a table 2, and may be reinforced by a cross bar 3. A main shaft 4 is mounted below the table and has a pinion 5 secured to one end. On the other end are loosely mounted the pulleys 6 and 7, which are belt-driven in opposite directions. A clutch-sleeve 8 is splined on the shaft and provided with sockets to receive the jaws 9 on the pulleys, so that the shaft will revolve in either direction, according to the pulley with which the clutch-sleeve is in engagement. Any other reversing mechanism may be employed.

Projecting upward from the table are the pedestals 10 between which are mounted the journal-boxes 11 of the rolls 12 and 13. On one end of the lower roll 13 is a gear 14 which meshes with the pinion 5, and on the other end, the gear 15 which meshes with the gear 16 on the upper roll. The upper roll 12

is provided with projecting rings 17 which enter grooves 18^a in the lower roll. The cross section of the edges of the rings and grooves (Fig. 6) is such that the ribs of the expanded metal shown in the Kane patent will fit the rolls.

On the front side of the table is secured a grooved plate 18, and on the rear edge a second grooved plate 19. The upper face of the latter is slightly inclined. Extending upward from the table are brackets or guides 20, between which is mounted the adjustable grooved apron 21, having side plates or lugs 22, adapted to be secured to the guides 20 by means of the bolts 23. The position of the apron is controlled by the screw 24 carried by the table.

The adjustment of the apron 21 is such that the plane of its upper face is always substantially tangent to those portions of the rings 17 which engage the upper surface of the sheet metal. It will be understood that the curvature given to the ribbed metal will depend upon the angle which the apron 21 makes with a plane passing through the axes of the rolls. As the apron is easily adjusted, the curvature can be quickly changed. When the apron lies down on the table, its upper surface is in the same plane with the plate 19, and the inclination of these plates to the horizontal will depend upon the greatest desired curvature of the ribbed metal.

It is sometimes desirable to reverse the rolls so that the sheet will receive a second treatment immediately, and also when it is desired to bend only a portion of the sheet. The mechanism for such reversing is as follows. To the caps 26 of the pedestals are secured the bearings 27 for the shaft 28. On this shaft is adjustably mounted an arm 29 carrying the adjustable plate 30 against which the sheet being rolled strikes, as indicated in dotted lines in Fig. 2 and thus swings up the arm 29 and turns the shaft 28. A hand lever 32 is also secured to this shaft whereby the shaft may be turned by the operator in either direction at will. To the right end of the shaft (left end in Fig. 4) is secured an arm 33, having its outer end bifurcated to receive the block 34 having trunnions 35, which trunnions are mounted in bearings in the bifurcated end. A pin 36 on the cap receives a sleeve 37 having a rod 38, which rod is slidable in a hole through the block 34. A

spring 39 on this rod presses the end of the arm 33 up or down while permitting it to swing across the line between the pin 36 and shaft 28, to hold the plate 30 in depressed or elevated positions. Brackets 40 project from the opposite pedestal and carry a shaft 41, on which is mounted a lever 42 whose lower end engages the pins 43 projecting from the sleeve 8. The upper end of this lever has a cam slot 44 in which a pin 45 on the arm 46 is slidable. This arm is secured to the shaft 28 and is swung up and down by the same. When the parts are as shown in Fig. 2, the machine is at rest, the pulleys 6 and 7 only, turning in the directions indicated by arrows.

The space between the rolls, when forced apart by the material between them, is controlled by the screws 48.

Many changes may be made in the details of construction without departing from the spirit of this invention.

The operation of the machine is as follows: The apron 21 having been properly adjusted and secured, the operator lifts the front end of the lever 32, thus starting the machine. The spring 39 holds up the lever 32 and also holds the clutch-sleeve 8 in engagement with the pulley 6. If the reversing mechanism is not employed, the machine will continue in motion in the same direction. Where the reversing mechanism is employed, the sheet will engage the plate 30 at the proper time and swing down the arm 46, sliding the sleeve 8 out of engagement with the pulley 6 and into engagement with the pulley 7. The arm 33 will be swung down from above the line between the pin 36 and shaft 28 to below it, where it will be held by the spring 39.

Having now explained my improvements, what I claim as my invention and desire to secure by Letters Patent is:—

1. In a bending-machine for ribbed sheet-metal, the combination of a lower roll having grooves to receive the ribs on the sheet metal, an upper roll having rings to enter the grooves, a plate to support the sheets as they are fed between the rolls, and an adjustable grooved plate to engage the sheets as they emerge from the rolls, and means to adjustably support said plate.

2. In a bending-machine for sheet-metal, the combination of a table, rolls mounted on said table, brackets extending upward from the table, an apron mounted between said brackets adjacent said rolls to engage the sheet metal as it leaves the rolls, and an adjusting screw mounted in said table to en-

gage the apron to control the inclination of 60 the same.

3. In a bending-machine for ribbed sheet-metal, the combination of a lower roll having grooves to receive the ribs on the sheet metal, an upper roll having rings to enter 65 the grooves, a grooved stationary plate to support the sheets as they are fed between the rolls, and an adjustable grooved plate to engage the sheets as they emerge from the rolls.

4. In a bending-machine for sheet-metal, the combination of a frame, bending rolls mounted thereon, a reversible driving mechanism for the rolls, a lever to control the driving mechanism, means to support the 75 sheet metal as it comes from the rolls, and means in the path of the sheet-metal and adapted to be shifted by the same for actuating the controlling lever to reverse the rolls.

5. In a bending-machine for sheet-metal, the combination of a frame, rolls mounted thereon, a reversible driving mechanism for the rolls, means to support the sheet metal as it comes from the rolls, and means adapted to be shifted by the sheet-metal as it passes through the rolls for reversing the driving mechanism.

6. In a bending-machine for sheet-metal, the combination of a frame, bending rolls 90 mounted thereon, mechanism for driving the rolls in either direction, a vertical reversing lever having a cam at its upper end, a shaft mounted on the frame having an arm in the path of the sheet-metal and adapted to 95 be oscillated by the same as it passes through the rolls, a second arm connected thereto and in engagement with the cam-end of the reversing lever, and means to hold said arms at either end of their movement.

7. In a bending-machine for sheet-metal, the combination of a frame, a pair of rolls mounted thereon, a plate to support the sheets as they are fed to the rolls, an apron mounted on said frame to engage the sheets 105 as they emerge from between the rolls, and a screw mounted on the frame and engaging the apron to adjust the inclination of the same with reference to said plate and thereby control the curvature of the metal sheets.

In testimony whereof I have signed this specification in the presence of two subscribing witnesses.

THOMAS HENRY KANE.
